UNITED STATES PATENT OFFICE.

CHARLES W. PEN DELL, OF CHICAGO, ILLINOIS, ASSIGNOR TO GENERAL ELECTRIC COMPANY, A CORPORATION OF NEW YORK.

AUTOMATIC SUBSTATION.

1,211,220.

Specification of Letters Patent.

Patented Jan. 2, 1917.

Application filed May 13, 1915. Serial No. 27,840.

To all whom it may concern:

Be it known that I, CHARLES W. PEN DELL, a citizen of the United States, residing at Chicago, in the county of Cook, State of Illinois, have invented certain new and useful Improvements in Automatic Substations, of which the following is a specification.

My invention relates to a supply of power for a distribution system, and more particularly to an arrangement of automatic substations adapted to be interposed between a distribution system and sources of power, and arranged to keep the supply practically uninterrupted.

With certain systems of distribution it is very desirable that there shall be practically no interruption in the supply of power. This is especially true when such apparatus as motor-driven fire pumps, electrically-operated railway signals, and the like, is supplied from the system in question. To avoid this possibility of a failure of power, it is sometimes possible to provide connections from a plurality of sources to the distribution system, switches being provided so that any one of these sources may be connected to the system. Upon the failure of one source of supply, it is disconnected and another source connected. Where this is done manually, communication between the switching points is necessary, and valuable time may be lost.

Accordingly, the object of my invention is to devise a system embodying automatic substations which are interposed between various sources of power and a distribution system, said substations embodying switching devices so arranged that the system will be automatically connected to a source which is alive, and to only one source. Furthermore, it may be desirable, where the sources of supply are owned by different companies, or for some other reason, to always connect the system to a particular source, if that source is alive; and if it is dead, to another particular source.

It is, therefore, another object of my invention to so arrange my system that the time required for the closing of the various switching devices is different for each device, with the result that the action is preferential.

Further objects of my invention will appear from a consideration of the following

description, taken in connection with the accompanying drawings, in which—

Figure 1 is a plan view of the operating mechanism for a switching device for one of my automatic substations; Fig. 2 is a side elevation of the same; Fig. 3 is a diagrammatic perspective view of this mechanism; Fig. 4 is a diagram of the electrical connections employed.

For the purpose of carrying out the desired operations of my novel system, a special form of switch operating mechanism has been devised, and I will first describe this mechanism, and will show how it was applied in my system. The actuating mechanism may be applied to any desired style of switch, and power for driving the same is supplied by means of a motor 10 connected with a worm and gear 11 by means of a flexible coupling 11a. Eccentrically mounted upon the shaft of this gear is an operating pawl 12, while concentrically mounted thereon is a holding pawl 13. These pawls are arranged to engage the teeth of a ratchet 14, which is suitably mounted to rotate on any convenient pivot, and is spring-pressed in a clockwise direction. This ratchet is provided with an outwardly-extending lug 15 designed to coöperate with a nose 16 upon the sleeve 17, which may conveniently be mounted to rotate on the same pivot as the ratchet 14. The sleeve 17 is connected, by means of a series of crank arms and links, with the actuating arm 18, which in turn is connected with the operating link 19 directly connected to the switch so that a downward movement of the link 19 effects the closing of the switch.

The operating arm 18 is held in its lowest position by means of a holding latch 20 which engages with a roller mounted on said arm, the latch 20 being held in engagement with the roller by gravity. The motion of this holding latch is limited in a counterclockwise direction by means of a nose 21 (see Fig. 2) which abuts against the base of the apparatus. When the latch 20 rotates into its holding position, the outer end of its lower arm engages with an upstanding trip latch 22, which is provided with a setting finger 23 and a tripping finger 24, and, as will be seen from Fig. 1, is offset from these fingers. This tripping latch 22 is brought into operative position positively by engagement of the lower arm 110

of the holding latch 20 with the setting finger 23. A low voltage trip coil 25 common in automatic switch mechanisms, is arranged, when energized, to hold up a weight 26, and when deenergized to release this weight so as to strike the tripping finger 24 and positively release the holding latch 20 through the agency of the setting finger 23. This weight 26 is raised to its upper position through the agency of a cam 27 acting against a roller arm 28 which is mounted on a sleeve with a finger 29. Counterclockwise rotation of the cam raises the finger 29 and lifts the weight.

The motor circuit is first closed, to start it in operation, by means of a low voltage relay 100, to be later described, but in order that the cycle of operations may be completed when the motor has once started, a cam-operated positive switch 30 is provided. This switch comprises fixedly mounted spring fingers 31 and a pivoted arm 32, and the pivoted arm is provided with a roller extension 33 which engages the surface of the cam 27 and is moved thereby, being held against said cam by means of a spring 34. At the upper end of the pivoted arm 32, and insulated therefrom, a contact member 35 is arranged to electrically connect the two spring fingers 31 when brought between said fingers by the action of the cam.

In order to predetermine the time required for closing the switch, the operating mechanism is provided with a selective device. This device comprises an adjustable arm 40, which is conveniently fixed upon the same shaft with the cam 27, and may be held in fixed relation to the ratchet 14 by bolting the two together at any one of the series of holes 41 (see Fig. 3). This adjustable arm is provided with a rear projection 42 which, in the initial position of the mechanism, abuts against an adjustable stop 43.

As previously described, it is desirable, for the proper operation of my system, that only one source shall be connected to the distribution system at any time. To this end I have provided a solenoid 50, responsive to the voltage of the distribution system. When energized, this solenoid is adapted to raise a core 51 and thereby rotate a bell crank lever 52 in a counterclockwise direction. This lever 52 is adjustably connected, by means of a link 53, with another bell crank lever 54, loosely mounted upon the shaft of the worm gear. The lever 54 is provided with a pin 55 which extends beneath the pawls 12 and 13, so that when the solenoid 50 is energized, the pin 55 will raise the pawls out of engagement with the ratchet. A brake arm 56, which is pivotally mounted in any convenient position, is operatively connected with the bell crank lever 52 by means of an adjusting

screw 57, so that when the solenoid 50 is energized, the brake will cause the motor 10 to stop almost immediately.

The application of this operative mechanism to my system will be now described, reference being had to Fig. 4, in which the mains 70 may be taken to represent those of the distribution system in question. This system may be considered as supplying power to the operating motors of railway signals, or to any other similar load. A plurality of sources of power, as indicated at 80 and 81, are adapted to be connected to this system by means of the switches 90 and 91, the switch 90 being shown in the open position, and the switch 91 in the closed position. Holding latches 120, corresponding to the latches 20 of the actuating mechanism, are diagrammatically illustrated as spring-pressed in one direction and held in operative locking position by the low voltage coil 25 when the same is energized. Power for driving the motors 10 of the actuating mechanism is supplied from the associated sources, the circuit being initially closed by means of low voltage relays 100 and 101, responsive to the voltage of the distribution system, when the relays are deenergized. The positively actuated switch 30 will, as soon as the motor starts, close the motor circuit and keep it closed until the cycle of operations is completed. If, however, owing to the selective arrangement of the various mechanisms, a switch is closed connecting the distribution system to a live source of power, then the relay 50 will be energized and the links 12 and 13 lifted, thereby allowing the ratchet 14 to be spring-pressed in a clockwise direction. The cam 27 will be similarly rotated to permit the opening of the positive switch 30. If the mechanism in question succeeds in closing the corresponding switch, then the solenoid 50 will still be energized, but not until the holding latch 20 is engaged with the roller on the actuating arm 18. Its only effect then will be to allow the ratchet to be rotated to its initial position by means of the associated spring.

What I claim as new and desire to secure by Letters Patent of the United States, is:—

1. The combination of a distribution system, a plurality of sources of power, one of which is connected to said system, automatically operated switching devices interposed between said sources and said system, and means responsive to an electrical condition of said system controlling the operation of said devices to put in service an idle source, upon the failure of the connected source.

2. The combination of a distribution system, a plurality of sources of power, automatically operated switching devices inter-

posed between said sources and said system, means responsive to an electrical condition of said system controlling the operation of said devices, and means for preventing the closure of more than one switch.

3. The combination of a distribution system, a plurality of sources of power, automatically operated switching devices interposed between said sources and said system, 10 means, comprising a relay responsive to the voltage of said system, for operating said switches when the voltage is substantially different from normal, and means responsive to the voltage of said system for rendering said operating means ineffective when the voltage is substantially normal.

4. The combination of a distribution system, a plurality of sources of power, automatically operated switching devices interposed between said sources and said system, 20 means, comprising a relay responsive to the voltage of said system, for operating said switches when the voltage is substantially different from normal, means responsive to the voltage of said system for rendering said operating means ineffective when the voltage is substantially normal, and means for varying the time of closing of said switches.

5. The combination of a distribution system, a plurality of sources of power, switching devices interposed between said system and said sources, electrical operating mechanisms for said switching devices arranged to be energized from the associated source, relay switches responsive to the voltage of said system arranged to energize an operating mechanism upon a failure of

voltage on said system, switches in parallel with said relay switches and controlled by 40 the movement of its controlling operating mechanisms, holding latches for said switching devices, low-voltage trip coils for said latches, and means associated with each switching device responsive to a predetermined potential difference on said system for rendering said operating mechanism ineffective.

6. The combination of a distribution system, a plurality of sources of power, switching devices interposed between said system and said sources, electrical operating mechanisms for said switching devices arranged to be energized from the associated source, 50 relay switches responsive to the voltage of said system arranged to energize an operating mechanism upon a failure of voltage on said system, switches in parallel with said relay switches and controlled by the movement of its controlling operating 55 mechanisms, holding latches for said switching devices, low-voltage trip coils for said latches, means associated with said switching devices responsive to a predetermined potential difference on said system 60 for rendering said operating mechanisms ineffective, and means for varying the time for closure of each switching device.

In witness whereof, I have hereunto set my hand this twenty-eighth day of April, 70 1915.

CHARLES W. PEN DELL.
